UNITED STATES PATENT OFFICE

EMMANUEL J. GREGORY, OF TOLEDO, OHIO, ASSIGNOR TO THE COMMONWEALTH MANUFACTURING COMPANY, OF TOLEDO, OHIO, A CORPORATION OF OHIO

CONVEYANCE LAMP

Application filed October 25, 1929. Serial No. 402,493.

My invention has for its object to provide a lamp, particularly adapted for use in connection with conveyances of different forms. Lamps embodying my invention have means 5 for confining the rays of light, projected by the lamp, beneath the level of the top of the lamp and, consequently, prevents the blinding that is produced by reflectors commonly used in lamps. By confining the rays of 10 light to a point below a horizontal plane through the lamp, an approaching conveyance, such as an approaching automobile, may be lighted and the rays of light will not rise to the eyes of the operator of the 15 conveyance. The invention particularly provides a reflector ridge that intercepts all rays of light that strikes the outer portions of the parabolic reflector, that are reflected upwards above the horizontal plane, that extends through the top of the lamp, and causes 20 the blinding of the eyes of the operator of an approaching automobile or other conveyance.

The invention may be used in connection 25 with double lighted bulbs and the lamps may be formed to reflect the rays from each of the bulbs and direct them in parallel relation towards the road; or each lamp may be lighted by a single bulb, wherein the rays of light 30 to the lower side of the reflector are intercepted, and directed to the upper side of the reflector to prevent the rays of light from being directed above the level of the top of the lamp.

The invention may be contained in structures of different forms and, to illustrate a practical application of the invention, I have selected a lamp embodying the invention as 40 an example of the various structures that contain my invention, and shall describe the lamp selected hereinafter. The lamp referred to is shown in the accompanying drawings.

Fig. 1 illustrates a vertical section through the lamp selected for purposes of illustration. Fig. 2 illustrates a transverse section of the lamp taken on the plane of the line 2—2 indicated in Fig. 1. Fig. 3 is a front view of 45 the forward part of the reflector of the lamp,

the part located in advance of the section line 2—2 indicated in Fig. 1.

The lamp is provided with the usual shell 1 that is suitably supported on the pedestal 2, or part of a bracket. The bracket may be 55 connected in any suitable manner to a part of the conveyance. The shell 1 is preferably ovoid in form, when the lamp is to be lighted by a single electric bulb; and when it is to be lighted by two bulbs, it preferably has 60 an oblong cross-section, as shown in Fig. 2. The shell 1 forms a protective shell for the reflector and the light bulbs.

The reflector is located within the shell 1 and conforms generally to the shape of the 65 shell 1. It is formed of two parts 4 and 5. The part 4 is formed of three portions, each of which has a configuration characteristic to itself. The portions merge into each other by curved surfaces to form a substantially 70 continuous inner reflector surface. Thus, the portion 6 is parabolic in form and joins with the portion 7 that extends spoon-shaped across the lower half of the parabolic portion 6, substantially to the horizontal plane 75 of the axis of the lamp. The portion 8 of the part 4 of the lamp is substantially ovoid in form and joins gradually by curved surfaces with the portions 6 and 7 of the part 4.

The part 5 of the lamp has the portions 9, 80 10, and 11, which are joined together by curved surfaces to form a continuous inner surface without any sharp corners. The portions 9 and 10 form the continuation of the portions 6 and 8, when the parts 4 and 85 5 are secured together. The portion 9 conforms to a truncated paraboloid, its larger diameter being located contiguous to the edge of the portion 6. The portion 11 is substantially spoon-shaped in its configuration, corresponding to the portion 7 of the part 4, and these portions form an intercepting ridge 19. The parts of the reflector 3 are formed of sheet metal and are supported within the shell 1 by means of a rib 15 that may be 90 formed of outwardly turned flanges 16 extending from the edges of the parts 4 and 5, the flange 16 of the outer edge of the part 4 being located in juxtaposed relation to the flange 16 that extends from the inner edge 95 100

of the part 5. To secure these parts together, the edge portions of the flanges may be folded, one over the other, as indicated at 18. The edges of the flanges 16 that form the ridge 15 fit the inner surface of the shell 1, and, to prevent movement of the parts 4 and 5, the flanges may be secured in position by suitable brackets, such as the brackets 17.

The reflector 3 may be secured in the shell 1 at its outer edge by suitably beaded and ribbed surfaces formed in the inner edge of a rim member 20, which may be secured in a spun groove 21, formed near the edge of the shell 1, by an inturned flange 22. The rim member 20 is formed to retain a ring 23, a flange 24, formed on the edge of the reflector 3, a ring 25, and the lens 26. The flange 24 is clamped between the rings 25 and 23, in the manner well known in the art.

The bulb 30 is of the type well known in the art, it being provided with a socket 31 that is adjustably supported in a bracket 32. The bracket 32 is supported on a ring 33 which conforms to, and is secured to, the small end of the reflector 3 by means of the flange 34 that may be spun over the inner edge of the ring 33. A second ring 35 is secured by means of the screws 36 to the ring 33. The bracket 32 has a flange 38 which is connected to the ring 33 by means of the screws 39. The bracket 32 has a cylindrical part 40 in which the socket member 31 is fitted. The cylindrical part 40 is provided with a pair of slots 42. The socket 31 has a cross bar 43 having end parts extending through the slots 42. A spring 44 surrounds the cylindrical part 40 and engages the ends of the cross bar 43. The exterior of the cylindrical part 40 is provided with threads, and a nut 45 is threaded onto the cylinder part and so as to engage the ends of the cross bar 43. The spring 44 operates to press the ends of the cross bar against the nut 45 and thus the bulb 30 may be readily adjusted with respect to the reflector.

In the operation of the lamp, the light will strike the parabolic parts 6 and 9 of the reflector and will be projected parallel to the axis of the lamp, the lamp being located the proper distance from the rear end of the reflector. It will also strike the portions 8 that form the sides of the lamp, and will be reflected forwardly. The rays will also strike the lower portions of the parabolic reflector part 6, but such rays will be intercepted and reflected by the spoon-shaped portion 7 and returned to the parabolic reflector 6, which will operate to direct the rays toward the road at a greater or less distance from the front of the lamp. Some of the rays will be reflected from the portion 9 of the part 5 to the part 11, which is dished sufficiently to cause all of such rays to be directed below the axis of the lamp. The portion 9 will angularly direct all diffused rays diagonally

downward. Thus, the invention affords a "non-glare" lamp particularly adapted for use on automobiles.

I claim:

In a conveyance lamp, a shell, a reflector located in the shell, the upper half of the reflector formed of two portions, the upper half of the inner portion conforming to a parabolic surface, the upper half of the outer portion conforming to a truncated paraboloid, the diameter of the said outer portion being larger at the edge of the first named portion, the lower half of the reflector having reentrant part formed of concave surfaces terminating in a ridge, flange portions extending from the ridge of the shell for locating and supporting the ridge in the shell substantially midway between the inner end of the reflector and the outer end and in the plane of the axis of the parabolic portions that form the upper half of the reflector, and an electric bulb located near the smaller end of the reflector.

In witness whereof I have hereunto signed my name to this specification.

EMMANUEL J. GREGORY.
